CLAIM

The ornamental design for a charger device, as shown and described.

DESCRIPTION

FIG. 1 is a top perspective view of a charger device;
FIG. 2 is a right side view of the charger device thereof;
FIG. 3 is a left side view of the charger device thereof;
FIG. 4 is a top view of the charger device thereof;
FIG. 5 is a bottom view of the charger device thereof;
FIG. 6 is a front view of the charger device thereof; and,
FIG. 7 is a back view of the charger device thereof.
The evenly spaced broken lines represent portions of the
charger device that form no part of the claimed design.
